SINK MOUNTING RIM

John S. Walsh, Toronto, Ontario, Canada, assignor to Geo. H. Hees Son & Company, Limited, Toronto, Ontario, Canada, a corporation of Canada

Application June 24, 1952, Serial No. 295,219

2 Claims. (Cl. 4—187)

1

This invention generally relates to a means for mounting a sink of the flat rim type within an opening in a drain board, cabinet top, or other supporting structure.

Various means have been provided in the past for mounting sinks of the flat rim type in supporting structures. Many of them have comprised a moulding with a T-shaped cross-section that extends around the sink rim, in combination with a clamp that carries a tightening means for engaging with either the sink or the drain board. My invention also relates to this general type of mounting means, that is, one having a moulding with a T-shaped cross-section and a clamp, but my invention differs from those previously known in that the means for tightening the clamp member is carried by the T-shaped moulding itself. This is an advantage because it simplifies the construction of the clamping member and results in an overall construction that is simple to use. The clamping members are items in the mounting means as a whole that are often misplaced and permanently lost. A reduction in their cost is then desirable because their loss or misplacement is not of such a consequence. The simpler clamping member is also easier to manipulate during installation.

According to my invention, I mount a flat sink rim in an opening of a supporting structure with moulding having a generally T-shaped cross-section, the top of which overlies adjacent edges of the sink and of the supporting structure and the leg of which extends between the adjacent edges of the sink and of the supporting structure. According to my invention, the leg portion of the moulding is formed with longitudinally spaced apart openings through which a clamping member can be inserted. The clamping member and openings are formed relative in size to each other so that the clamping member has free movement within the opening towards or away from the top of the T cross-section of the moulding frame. The clamping member within the opening is tightened against the under side of the sink rim and the under side of the supporting structure, in use, by means of a tightening screw or its equivalent that is carried by or mounted on the moulding itself. The invention will be clearly understood after reference to the following detailed specification taken in conjunction with the drawings.

In the drawings:

Figure 1 is a sectional view illustrating the means for mounting a flat rimmed sink within a supporting structure according to the present invention.

2

Figure 2 is a broken view along the line 2—2 of Figure 1 illustrating the two spaced apart clamping brackets.

Figure 3 is an exploded view illustrating the component parts of a means for mounting a sink rim according to the present invention.

Figure 4 is a perspective view illustrating a sink mounted within a drain board according to the present invention.

10 Referring to the drawings, the numeral 10 indicates a sink of the flat rim type, mounted on the drain board 11 of a cabinet 12.

My invention relates to a means for mounting the sink 10 on the drain board 11 and it comprises a moulding 13 adapted to extend around the entire outer edge of the sink as illustrated in Figure 4, and having a T-shaped cross-section as illustrated in Figure 1 and Figure 3. In use, the top of the T-shaped moulding overlies adjacent edges of the drain board 11 and of the flat rim 14 of the sink 10 as illustrated in Figure 1 of the drawings. The moulding, of course, continues entirely around the sink as illustrated in Figure 4 of the drawings. The leg of the T-shaped cross-section of the moulding 13 extends downwardly between the edge of the drain board 11 and of the rim 14, also as illustrated in Figure 1 of the drawings.

According to my invention, the leg portion 30 of the moulding 13 is formed with longitudinally spaced apart openings 15 which are designed in use to receive clamping members 16, one end of which is designed to engage with the sink rim and the other end of which is designed to engage with the drain board. The height of the openings 15 is such that the clamping members 16 can move within the openings 15 towards or away from the top of the moulding. Openings 15 are preferably six inches to ten inches apart, but can be located as close together or as far apart as it is desired to have the clamping members 16 for the sink.

45 A clamp tightening member 17 is carried by the leg portion of the moulding 13 and, in the embodiment of the invention shown, comprises a screw 17 that threads into a passage 18 that communicates with the bottom of the opening 15 and the bottom edge of the leg portion of the moulding 13. It will be apparent that by tightening or loosening the thumb screw 17 against a clamping member 16 that is inserted through the opening 15 that the clamping member can be caused to move within openings 15 towards or against the top portion of the T-shaped moulding or into or out of clamping engagement with the bottom of the drain board 11 and sink rim 14.

To accommodate the difference in thickness of the drain board 11 and the flat sink rim 14, I provide an L-shaped clamping member 16, the base of which is designed to engage with the under side of the sink rim and the leg portion of which is designed to engage with the under side of the drain board under the tightening force of the screw 17.

Embodiments of my invention other than the one shown will be apparent to those skilled in the art and it is not my intention that my claims should be limited thereto. The essence of my invention is the provision of a means for mounting a flat rim sink employing a rim moulding having a T-shaped cross-section in which the clamp tightening means are carried by the moulding itself and engage with a clamp that is inserted through an enlarged opening in the leg portion of the T-shaped moulding.

What I claim as my invention is:

1. In a device for mounting a sink in an opening in a supporting structure, a moulding having a T-shaped cross-section, the top of said T being adapted to overlie adjacent edges of the sink rim and supporting structure, the leg of said T being adapted to extend therebetween, a clamping member having one end for engaging the under side of a sink supporting structure and its other end for engaging the under side of a sink rim, an adjustable clamping member sustaining and tightening means carried by the leg of said T moulding, the upper end thereof being adapted for operative engagement with said clamping member between the ends of the

latter member to sustain it, said leg of said T-shaped moulding being formed with an opening, said clamping member sustaining and tightening means comprising a bolt, the leg of said T-shaped moulding being formed with a threaded hole for said bolt extending from the lower edge of said leg to said opening, said bolt being threaded into said threaded hole from the bottom edge of said leg whereby the free end thereof enters said opening, said opening being adapted to receive said clamping member therethrough with the ends of the latter underlying opposite sides of the top of said T section and having a depth greater than the thickness of said clamping member whereby said clamping member can be tightened towards the top of said T as said bolt is threaded into said threaded hole.

2. A device for mounting a sink in an opening of a supporting structure as claimed in claim 1, in which said clamping member is L-shaped, the base of the L being adapted to account for the difference in thickness between said supporting structure and the rim of the sink.
